UNITED STATES PATENT OFFICE.

CLARENCE E. CHATFIELD, OF BUFFALO, NEW YORK, ASSIGNOR TO THE SIMMEN AUTOMATIC RAILWAY SIGNAL COMPANY, OF BUFFALO, NEW YORK, A CORPORATION OF ARIZONA.

RAILWAY SIGNAL SYSTEM.

1,361,016.

Specification of Letters Patent.

Patented Dec. 7, 1920.

Application filed July 20, 1917. Serial No. 181,873.

To all whom it may concern:

Be it known that I, CLARENCE E. CHATFIELD, a citizen of the United States, residing at Buffalo, in the county of Erie, and State 5 of New York, have invented certain new and useful Improvements in Railway Signal Systems, of which the following is a specification.

This invention relates to a railway signal 10 system and more particularly to a system to facilitate reverse movements on a railway track in which the train movements are normally in one direction.

In present practice multiple track rail- 15 ways in which the traffic on each track is normally in a given direction, are protected by automatic signals which provide for the movement of trains in the normal direction of traffic only. If it is desired to move a 20 train in the reverse direction, all of the signals, are set at danger ahead of the train as it progresses along the trackway, and the operator of such a train has no knowledge as to the condition of the track ahead of 25 him. In a few cases, where traffic in the reverse direction is extremely heavy, it has been found desirable to equip such tracks with signals which are ordinarily used for single track railroads. This gives as much 30 protection to a train running in one direc- 80 tion as to a train running in the other direction, but is so expensive that such an application of signals has not found broad use. It is the object of my invention to pro- 35 vide a signal system which normally pro- 85 tects trains running in the normal direction of traffic, but is also arranged to give protection to trains running in the reverse direction.

40 Other objects and advantages will appear as the description of the invention pro- 90 gresses, and the novel features will be particu- 95 larly pointed out in the appended claims.

In describing the invention in detail, 45 reference is had to the accompanying drawing wherein I have illustrated in diagram- 95 matic form a preferred physical embodiment of my invention, and wherein like characters of reference designate corre- 50 sponding parts in the several blocks.

In the drawing, 1, 1 are the rails of a trackway, which is divided by insulated joints 2, 2 into three main blocks, A, B and C, these main blocks being divided by further insulating joints 2, 2 into sub-blocks 55 A¹, A² and A³, which are parts of the main block A; B¹, B² and B³, which are parts of the main block B; and C¹, C² and C³, which are parts of the main block C. The normal direction of traffic over the trackway is 60 from right to left, as indicated by the arrow.

As the main blocks, A, B and C are identi- 65 cal, I will merely describe the apparatus relating to the main block A. At the end 70 of the main block A, at which trains enter the block in the normal direction of traffic, is located a signal 3^a. This signal may be any type of signal which is well known in the art for giving indications to the operator of an approaching train, and I have not considered it necessary to show a detailed view of such signal. I wish it understood, however, that this signal, in what- 75 ever form it may be, would be arranged to give indications in both directions. That is, a train approaching in either direction, would obtain a distinctive indication by day or by night, of the position of the signal. 80

Each sub-block A¹, A² and A³ has at one end a track battery 4, which is connected by suitable conductors to the track rails. Connected to the opposite end of the rails of the sub-block A¹, by the wires 39^a and 40^a, is 85 the track relay 5^a. The track relay 5^a is nor- 90 mally energized through the following cir- 95 cuit: from the positive side of the track battery 4 to the rail, wire 39^a, track relay 5^a, wire 40^a, track rail to the negative side 100 of the battery 4. The track relay 5^a has five neutral armatures, 11^a, 12^a, 13^a, 14^a and 15^a. When the track relay 5^a is energized, the armatures 11^a, 12^a and 14^a are adapted to touch the contacts 21^a, 22^a, and 24^a re- 95 spectively, and when the relay is deener- 100 gized the armatures 13^a and 15^a are adapted to touch the contacts 23^a and 25^a respec- tively.

Connected to the rails at the end of the sub-

block A² by the wires 49^a and 50^a is the track relay 6^a. The track relay 6^a is normally energized through the following circuit: from the positive side of the battery 4 to the track rail, wire 49^a, relay 6^a, wire 50^a, track rail to the negative side of the battery 4. The relay 6^a has five neutral armatures—16^a, 17^a, 18^a, 19^a and 20^a. When the relay 6^a is energized the armatures 16^a, 17^a and 20^a are adapted to touch the contacts 26^a, 27^a and 30^a respectively, and when the relay is deenergized, the armatures 18^a and 19^a are adapted to touch the contacts 28^a and 29^a respectively.

15. Connected to the track rails of the sub-block A³ by the wires 51^a and 52^a is the track relay 7^a. The relay 7^a is normally energized through the following circuit: from the positive side of the battery 4 to the track rail, wire 51^a, relay 7^a, wire 52^a, track rail to the negative side of the battery 4. The relay 7^a has three neutral armatures 31^a, 32^a, and 33^a, which are adapted, when the relay 7^a is energized, to touch the contacts 41^a, 42^a and 43^a respectively.

20. There is also related to the block A an auxiliary relay 8^a. The relay 8^a has two neutral armatures 34^a and 35^a. When the relay 8^a is energized, the armature 34^a is adapted to touch the contact 44^a, and when the relay is deenergized the armature 35^a is adapted to touch the contact 45^a. The relay 8^a is normally deenergized.

25. There is related to the block A a reverse traffic control relay 9^a. The relay 9^a has three neutral armatures 36^a, 37^a and 38^a. When the relay 9^a is energized, the armatures 36^a and 37^a are adapted to touch the contacts 46^a and 47^a, and when the relay is deenergized, the armature 38^a is adapted to touch contact 48^a. The relay 9^a is normally deenergized. There is also related to the block A a signal battery 10^a. The parts which have been described are suitably connected by electrical conductors or wires which will be more fully described in the description of circuits hereinafter set forth.

30. Normally, the signal 3^a is held in the clear position through the following circuit: from the positive side of the battery 10^a to the wire 54^a, signal 3^a, wire 53^a, 75^b, armature 38^b, contact 48^b, wire 73^b, contact 41^a, armature 31^a, wire 58^a, contact 26^a, armature 16^a, wire 57^a, contact 21^a, armature 11^a, wire 56^a, wire 55^a to the negative side of the battery 10^a.

35. Let us now assume that a train is approaching the signal 3^a in the normal direction of traffic. The signal 3^a will be in the clear position provided there is no train occupying any part of the block A and also provided that there is no train in the sub-blocks B¹ or B² moving in the reverse direction. As soon as the assumed train has

40. passed the signal 3^a and entered the sub-block A¹, the track relay 5^a will become deenergized due to the short circuiting of the track battery 4 by the wheels of the train. This will cause the signal 3^a to assume the danger position as its control circuit is now broken at the contact 21^a. It will also cause the auxiliary relay 8^a to become energized through the following circuit: from the positive side of the battery 10^a to the wire 66^a, wire 67^a, contact 30^a, armature 20^a, wire 71^a, contact 25^a, armature 15^a, wire 77^a, relay 8^a, wire 55^a to the negative side of the battery 10^a. The energizing of the relay 8^a, closes a stick circuit for this relay as follows: from the positive side of the battery 10^a to the wire 66^a, wire 65^a, contact 23^a, armature 13^a, wire 63^a, armature 34^a, contact 44^a, wire 78^a, relay 8^a, wire 55^a to the negative side of the battery 10^a.

45. When the train passes into the sub-block A², the track relay 6^a will become deenergized due to the short circuiting of its corresponding track battery 4 by the wheels of the train. This will cause the signal 3^a to still remain at danger, as its control circuit is now broken at the contact 26^a, while the operating circuit of the auxiliary relay 8^a is now broken at the contact 30^a, this relay will still remain energized, as its stick circuit is still closed, as follows: from the positive side of the battery 10^a to the wire 66^a, wire 65^a, wire 64^a, contact 28^a, armature 18^a, wire 62^a, wire 63^a, armature 34^a, contact 44^a, wire 78^a, relay 8^a, wire 55^a to the negative side of the battery 10^a.

50. When the train enters the sub-block A³, the track relay 7^a will become deenergized due to the short circuiting of its corresponding track battery 4 by the wheels of the train; thus the signal 3^a will remain in the danger position, due to the opening of its control circuit at the contact 41^a. The auxiliary relay 8^a will again become deenergized as soon as the train clears the sub-block A² due to the opening of its stick circuit at the contact 28^a.

55. The passage of the train through blocks B and C will result in operations similar to those described for block A.

60. Let us now assume that a train is approaching the block C in the reverse direction of movement. As soon as the train enters the sub-block C³, the track relay 7^c will be deenergized due to the short circuiting of its corresponding track battery 4 by the wheels of the train. This will maintain the signal 3^c at danger, due to the opening of its control circuit at the contact 41^c. The signal 3^c will have been previously set at danger due to the energizing of the reverse traffic control relay in the block through which the train has just passed. A similar operation will be hereinafter described,

when the signal 3^b will be set at danger due to the energizing of the reverse traffic control relay 9^c.

As soon as the train enters the sub-block 5 C², the track relay 6^c will be deenergized due to the short circuiting of its corresponding track battery 4 by the wheels of the train. This causes the opening of the normal control circuit for the signal 3^c at the 10 contact 26^c but the signal 3^c will be cleared as hereinafter described. It will also cause the reverse traffic control relay 9^c to become energized through the following circuit: from the positive side of the battery 10^c to the wire 66^c, armature 35^c, contact 45^c, wire 72^c, armature 14^c, contact 24^c, wire 79^c, armature 19^c, contact 29^c, wire 68^c, relay 9^c, wire 70^c, and wire 55^c to the negative side of the battery 10^c. The energizing of the relay 9^c closes a stick circuit for this relay as follows: from the positive side of the battery 10^c, to the wire 66^c, wire 81^c, contact 43^b, armature 33^b, wire 76^c, armature 36^c, contact 46^c, wire 69^c, relay 9^c, wire 70^c, wire 55^c, 15 to the negative side of the battery 10^c. The energizing of the relay 9^c sets the signal 3^b at danger as the control circuit for this signal is now broken at the contact 48^c. The energizing of the relay 9^c, provided no train 20 is occupying any part of the block B, sets the signal 3^c at clear through the following circuit: from the positive side of the battery 10^c to the wire 54^c, signal 3^c, wire 53^c, wire 74^c, contact 47^c, armature 37^c, wire 59^c, armature 12^b, contact 22^b, wire 60^b, armature 17^b, contact 27^b, wire 61^b, armature 32^b, contact 42^b, wire 80^c, wire 55^c to the negative 25 side of the battery 10^c.

When the train enters the sub-block C¹, 40 the track relay 5^c becomes deenergized due to the short circuiting of its corresponding track battery 4 by the wheels of the train. This, however, does not set the signal 3^c at danger, as this signal is still held at clear by 45 the circuit through the contacts of the reverse traffic control relay 9^c, as it has heretofore been described. While the deenergizing of the relay 5^c opens the operating circuit of the relay 9^c at the contact 24^c, this 50 relay does not become deenergized as its holding circuit, which has heretofore been described, is still closed; thus the signal 3^c remains at clear.

As soon as the train passes the signal 3^c 55 and enters the sub-block B³, the track relay 7^b will become deenergized. This will cause the reverse traffic control relay 9^c to again become deenergized due to the opening of its stick circuit at the contact 43^b, and the signal 3^c will therefore, again go to the danger position. As soon as the wheels of the train clear the sub-block C¹, the signal 3^c 60 will again go to the clear position, due to the closing of its normal control circuit at

the contact 21^c. It will be noted, however, 65 that the signal 3^c cannot again be cleared by a following train until the first train has left the block B.

The progress of the train through the block B and the block A will result in operations similar to those described for its passage through the block C. 70

It will be observed that the operation of the auxiliary relays and the reverse traffic control relays differ according to the direction of the train. For example, considering block B, when a train enters the block in the normal direction of traffic, the auxiliary relay 8^b becomes energized, and remains energized as long as the train is in the sub-blocks 75 B¹ and B². As the operating circuit of the reverse traffic control relay 9^b is taken through the back contact 45^b of the auxiliary relay 8^b, it will be obvious that a train moving through the block in the normal direction of traffic cannot cause the reverse traffic control relay 9^b to become energized. It will also be noted that when a train is moving through the block B in the reverse direction of traffic, the reverse traffic control relay 9^b 80 will become energized when the train enters the sub-block B² and will remain energized until the train enters sub-block A³.

While I have shown fixed signals for advising train operators of the condition of the 95 track, I wish it understood that I do not mean by this particular specific showing to exclude the use of other and well known equivalents of fixed signals, as it is well known to those skilled in the railway signaling art that whether or not ramp-rails and cab signals are substituted for fixed signals is well within the skill of those versed in the art of railway signaling.

Although I have particularly described 105 the construction of one physical embodiment of my invention, and explained the operation and principle thereof, nevertheless, I desire to have it understood that the form selected is merely illustrative, but does not 110 exhaust the possible physical embodiments of the idea of means underlying my invention.

What I claim as new and desire to secure by Letters Patent of the United States is: 115

1. In a railway signal system, a trackway divided into blocks, a signal at the entrance to each block, means for normally holding said signal in the clear position, means for setting said signal to the danger position 120 when a train, moving in a direction opposite to the normal direction of traffic, approaches the block, and means for returning said signal to the clear position as said train progresses through the block.

2. In a railway signal system, a trackway divided into blocks, a signal at the entrance to each block, means for normally holding

4
said signal in the clear position, means for setting said signal to the danger position when a train, moving in a direction opposite to the normal direction of traffic, approaches the block, and means for returning said signal to the clear position as said train progresses through the block, provided the block in advance of the train is clear.

3. In a railway signal system, a trackway 10 divided into blocks, a signal at the entrance to each block, means for normally holding said signal in the clear position, means for setting said signal to the danger position and maintaining it in the danger position as 15 a train progresses through the block, moving in the normal direction of traffic, means for setting said signal to the danger position when a train moving in a direction opposite to the normal direction of traffic approaches the block, and means for returning said 20 signal to the clear position as said train progresses through the block.

4. In a railway signal system, a trackway 25 divided into blocks, a signal at the entrance to each block, two means for operating said signal to and holding said signal in the clear position, one of said means normally operating said signal to and holding it in the clear position, and the other means including a normally open circuit operating said signal to and holding it in the clear 30 position when said signal is approached by a train moving in a direction opposite to the normal direction of traffic.

35 5. In a railway signal system, a trackway divided into blocks, a signal at the entrance to each block, two means for operating said signal to and holding said signal in the clear position, one of said means normally operating said signal to and holding it in the clear 40 position and the other means including a normally open circuit operating said signal to and holding it in the clear position when said signal is approached by a train moving 45 in a direction opposite to the normal direction of traffic, provided the block in advance of the train is clear.

6. In a railway signal system, a trackway 50 divided into main blocks, each of said main blocks being divided into a plurality of sub-blocks, a normally closed track circuit for each sub-block, a reverse traffic control relay associated with each main block, means including a normally open circuit for operating said 55 reverse traffic control relay when a train passes through the main block in a direction opposite to the normal direction of traffic and further means for preventing the operation of said relay when a train passes through 60 the block in the normal direction.

7. In a railway signal system, a trackway 65 divided into main blocks, each of said main blocks being divided into a plurality of sub-blocks, a normally closed track circuit for

each sub-block, a reverse traffic control relay 65 associated with each main block, a signal at the entrance to each main block, means including a normally open circuit controller operated by said reverse traffic control relay for setting said signal in the clear position, 70 means for operating said reverse traffic control relay when a train passes through the main block in a direction opposite to the normal direction of traffic and further means for preventing the operation of said relay 75 when a train passes through the block in the normal direction.

8. In a railway signal system, a trackway 80 divided into blocks, a signal at the entrance to each block, means for normally holding said signal in the clear position when the block is unoccupied and when no train is approaching the block, moving in a direction opposite to the normal direction of traffic, means for setting said signal to danger 85 and maintaining it at danger when a train moving in the normal direction of traffic occupies the block, means for setting the signal at danger when a train moving in a direction opposite to the normal direction 90 of traffic approaches the block, and means for returning the signal to the clear position as said train progresses through the block, provided the block in advance of the 95 said train is clear.

9. In a railway signal system, a trackway 100 divided into main blocks, each of said main blocks being divided into a plurality of sub-blocks, a normally closed track circuit for each sub-block, a signal at the entrance to each main block, a normally de-energized reverse traffic control relay associated with each main block, a circuit for normally holding said signal in the clear position, said circuit including the front contacts of the track relays of the sub-blocks included in the main block with which the signal is associated, and the back contact of the reverse traffic control relay in the block in advance, and a second circuit for moving said 105 signal to the clear position when a train is moving through the block in the reverse direction, said circuit including the front contact of the reverse traffic control relay in the block with which the signal is associated, 110 and the front contacts of the track relays of the sub-blocks included in the main block in the rear of the said signal.

10. In a railway signal system, a trackway 115 divided into main blocks, each of said main blocks being divided into a plurality of sub-blocks, a normally closed track circuit for each sub-block, a signal at the entrance to each main block, a normally de-energized reverse traffic control relay associated with each main block, means for maintaining the said relay deenergized when a train passes through the block in the non- 120 125

mal direction of traffic, further means for energizing said relay when a train passes through the block in the reverse direction, a circuit for normally holding said signal in the clear position, said circuit including the front contacts of the track relays of the sub-blocks included in the main block with which the signal is associated, and the back contact of the reverse traffic control relay 10 in the block in advance, and a second circuit

for moving said signal to the clear position when a train is moving through the block in the reverse direction, said circuit including the front contact of the reverse traffic control relay in the block with which the 15 signal is associated, and the front contacts of the track relays of the sub-blocks included in the main block in the rear of the said signal.

CLARENCE E. CHATFIELD.
